DUPLICATING RIBBON ATTACHMENT

Julius C. Hochman, New York, N. Y.

Application January 19, 1953, Serial No. 331,942

21 Claims. (Cl. 197—153)

This invention relates primarily to bookkeeping machines, more particularly to the instrumentalities thereof or associated therewith for producing simultaneously two or more separate inked copies.

It is a primary object of the invention to render serviceable any of the various conventional makes of bookkeeping machines without any alteration whatsoever in the construction thereof, for simultaneously producing two or more non-smudging inked, typewritten copies of documents such as journal sheets, ledger cards, bills or the like which would smudge in the considerable handling during the normal course of business if made with conventional carbon paper.

Another object is to provide means for accomplishing the above result which may be set or arranged for use with as great or greater facility than carbon paper, (that is awkward to use especially when large sheets are required for relatively large ledger cards or journal sheets that may run from 17 inches in length to 30 inches in width) which is more economical than carbon paper, which requires less frequent handling for removing and replacing the duplicating element used according to this invention in place of carbon paper and wholly obviates the special precautions and operations required in effecting erasures in the course of typing where carbon paper is used.

Another object is to provide for accomplishing the above results, an auxiliary ribbon supporting attachment or accessory device of simple construction, which may be securely retained on the machine and which automatically exposes continually changing areas of ribbon to type impact and throughout the use thereof, automatically maintains the ribbon in sufficiently taut condition for best service.

Another object is to provide an auxiliary ribbon holder of the above type from which the ribbon may be readily removed and upon which the ribbon may be rearranged for utilizing fresh areas thereof, or a new ribbon affixed by simple manipulation without danger of smudging the fingers.

Another object is to provide a ribbon frame of the above type, which may be formed substantially solely from metal stampings, which in use may be readily applied upon the machine, without resort to tools, or skilled or time consuming fastening manipulation and which may as readily be removed from the machine, which co-ordinates with the parts of the machine automatically to assure proper co-relation for effective use, which does not interfere with the normal operation of the paper clamps, bail or other paper holding means or the line spacer, and which is free from interference with the primary ribbon mechanism.

Another object is to provide frames of the above type which readily admit of the use of more than one ribbon on a single ribbon carrying element or the use of more than one ribbon carrying element for the preparation simultaneously of more than one inked typewritten copy in addition to the single typewritten copy for which the bookkeeping machine is designed.

Another object is to provide a device of the above type for use with front feed type bookkeeping machines, that makes collated form insertion faster and more accurate than when conventional carbon paper is used with such machine.

Another object is to provide a device of the above type that may be readily adjusted so as to fit between the component elements of a bookkeeping machine.

Another object is to provide a ribbon holder of the above type which in operative position will retain a ribbon thereon so as to afford substantially complete visibility of the paper immediately therebelow.

It is among the objects to provide a holder of the above type which performs one or more of the following functions: (a) so to retain a ribbon that the type heads will strike near its top edge and thereby afford complete visibility of the typed line upon rotation of the platen one space, (b) to afford visibility of certain portions of the line, while still permitting typing at the other ribbon covered portions, without loss of ribbon tension and (c) to afford complete utilization of the rest of the ribbon upon end to end reversal of the ribbon on said holder and thereby permit utilization of its entire effective area.

A feature of the invention is the use of an open frame, carrying one or more ribbons and so constructed that it becomes inherently coordinated with a conventional bookkeeping machine when simply positioned near the platen, thereby serving to imprint additional inked copies, the frame with its carried ribbons being free for shifting longitudinally with each movement of the platen after each typing operation and thereby avoiding exposure of the identical ribbon area to successive type impacts.

In a preferred construction, the frame is a substantially rigid generally U-shaped metal piece, to rest against and with its cross bar extending longitudinally of the platen, an inked ribbon being releasably attached to bridge between the free ends of the arms of said frame, which extend downward from the bar and are preferably curved to conform to the platen.

Another feature is the construction of the ribbon carrying arms of the frame in such manner as normally to urge a ribbon thereon away from the platen in order to facilitate insertion and positioning of two front fed forms one in front of and one behind the ribbon and in front of the platen of a front feed throat type machine exemplified by the well known National Cash Register class 3000 Bookkeeping Machine and automatically to position said ribbon adjacent said platen when the front feed throat is closed.

This application is a continuation-in-part of my co-pending application Serial No. 37,748 filed July 9, 1948, and issued as Patent No. 2,626,035 on January 20, 1953.

In the accompanying drawings in which are shown one or more of various possible embodiments of the several features of the invention,

Fig. 1 is a fragmentary transverse cross sectional view in closed position of an open throat type bookkeeping machine with a two ribbon auxiliary ribbon attachment in position thereon,

Fig. 2 is a view similar to Fig. 1 showing the machine in open or form inserting and removing position,

Fig. 3 is a perspective view, in open position, on a larger scale, of the embodiment of the device shown in Figs. 1 and 2,

Fig. 4 is a fragmentary perspective view of a ribbon for use with the device,

Fig. 5 is a fragmentary perspective view similar to Fig. 3 of the device in closed position,

Fig. 6 is an exploded fragmentary perspective view of the device,

Fig. 7 is an end elevational view on a somewhat larger scale, taken along line 7—7 of Fig. 5, the parts being

slightly separated, more clearly to show the details of construction.

Fig. 8 is a fragmentary detail view of the pivotal mount of the ribbon holder,

Fig. 9 is a fragmentary detail view of the pivoted ribbon holder,

Fig. 10 is a fragmentary perspective view of another embodiment, for use with machines in which the typing is performed from beneath the platen and in which free access to the platen is obstructed by carriage elements, and

Fig. 11 is a fragmentary transverse cross sectional view of the device shown in Fig. 10 mounted on a machine.

Referring now to the drawings, the device shown in Figs. 1 to 8 is especially designed for use with book-keeping machines, illustratively of the front feed throat type such as that sold by the National Cash Register Company, to make entries as, for example, on a statement sheet, a ledger sheet and a journal sheet.

As is diagrammatically shown in Figs. 1 and 2, such machine desirably comprises a platen 11 having a bail rod 12 associated therewith that carries rollers 13 and a rod 14 which extends longitudinally of the platen upon which the ribbon frame 20 shown in Fig. 3 may be removably mounted.

Associated with the platen 11 is a front plate 15, usually of lucite or other transparent plastic and a paper table 16, said paper table 16, said platen 11 and said plate 15 being movable from the closed operating position of the machine shown in Fig. 1 to the open or form insertion or removal position shown in Fig. 2.

The ribbon frame 20 shown in Fig. 3, to be used in conjunction with such bookkeeping machine, desirably comprises a spring metal angle bar 21 having lengths 26 and 24 at right angles to each other and of length nearly equal to that of the platen 11. Bar 21 desirably has parallel arms 22 affixed as by rivets 23 to the ends thereof or formed integral therewith if desired, said arms extending at right angles to bar 21.

In the illustrative embodiment herein, the root portion 22' of each arm 22 is bent outward at its extremity to define a lug 25 which fits snugly against the portion 26 of bar 21, protrudes beyond its longitudinal edge and the outer extremity of said lug is reversely bent to form a spring clip member 27 with an upturned end 28. The root portion 22' of each arm 22 also has an outwardly bent lug 29 adjacent the clip 27 and spaced slightly therefrom, the outer part of said lug 29 being bent downward to extend parallel to portion 24 of angle bar 21.

The outer portion of each arm 22 is desirably curved as at 23 generally to conform to the curvature of the platen 11.

Each of the arms 22 may be tapered as at 30 along the outer edge thereof from the beginning of the curved portion 23 as at 31 to near the end thereof as at 32 (Figs. 3 and 6) so that the width of the arms progressively decreases.

Each arm 22 may have at its end an extension 35 directed laterally outward and transversely aligned upstanding ears 36, 37 are desirably formed respectively at the extremity of extension 35 and the inner edge 38 of the arm 22, each ear having an opening therethrough. In addition, each arm at the end thereof has a reversely bent stop 41 positioned substantially midway between the ears 36 and 37.

A pivoted ribbon holder 42, desirably comprises a strip of resilient spring metal reversely bent at 43 and curved to conform generally to platen 11. The holder 42 desirably has laterally extending studs 44, preferably formed integral with and at the ends of its reversely bent end 43, said studs fitting into the openings in ears 36, 37 pivotally to mount the ribbon holder. As shown in Figs. 3 and 6 the stop 41 serves to limit the outward pivotal movement of said holder 42.

The pivotal axis of ribbon holder 42 is preferably inclined inwardly, which may readily be accomplished in

any of a plurality of ways and as shown in Fig. 8, preferably by making the opening in outer ear 36 further from the surface of arms 22 than the opening in ear 37.

The outer ply 45 of ribbon holder 42 extends upwardly beyond the inner ply 46 to afford a closing lever 47, the free end 48 of which is curved inwardly slightly as shown. The inner ply 46 as shown in Fig. 9 is of reduced width near its free end which is substantially rectangular in shape as at 49 and has a ribbon retaining or lock shoulder 51 integral with its outer edge.

The outer ply 45 desirably has a ribbon guarding arm 52, extending laterally outward from its outer edge 53, which is bent inwardly slightly as at 54, said arm extending slightly beyond and over the rectangular ribbon holding portion 49 of inner ply 46.

A second or journal sheet ribbon holder 55 is provided, desirably comprising a substantially L-shaped member of thin resilient spring metal. One arm 56 of holder 55 may extend transversely across the curved portion 23 of arm 22 to which it is affixed as by rivets 57. The other arm 58 of the holder 55 is relatively narrow in width and of stiffness less than arm 22, is curved to conform substantially to the platen and extends along the outer edge 30 of arm 23 toward its free end. The free end of arm 58 is reduced in width and is substantially rectangular in shape as at 61 and has a ribbon retaining or lock shoulder 62 integral with its outer edge.

The guard arm 52 of outer ply 45 is so positioned that when moved against ribbon holder arm 58 it will be aligned with and project outward beyond the rectangular ribbon holding portion thereof.

Ink-impregnated ribbons 63 and 64 are positioned on the ends 49 and 61 of ribbon holder 42 and 58 respectively. Each of the ribbons desirably has end tabs 65 preferably of impervious fabric affixed thereon as shown in Fig. 4 with slits 66 and 67 therein through the tab and the ribbon which may extend parallel to the length of the ribbon and may be of equal length to be accommodated upon the ends 49 and 61. It is of course to be understood that were the ribbon ends appropriately impregnated or coated to stiffen them sufficiently, the tabs 65 could be eliminated and the slits 66 and 67 through the ribbon alone could accommodate ends 49 or 61.

In mounting the ribbon upon the frame, the application of the tabs over the ends 49 results in tension of the ribbon due to slight bowing of bar 21. By reason of the fact that the pivotal axis of ribbon holders 42 are inclined inwardly and as ribbon 63 will be under considerable tension, the ribbon holders 42 will normally and automatically pivot away from the arms 22 as is clearly shown in Fig. 3.

The application of the tabs over the ends 61 of arms 58 also results in tension on the ribbon 64, the arms 58 yielding slightly and maintaining such tension without substantially affecting the tension on ribbon 63.

As the distance between the outer edges of the slits in the ribbon is shorter than the distance between the outer edge of the ribbon attaching ends 49 and 61, the lock shoulders 51 and 62 respectively will snap under the outer ends of top slits 66 when installed, thereby securely retaining the ribbons in place yet permitting ready removal when desired.

The frame 20 above described is installed with the spring clip portion 27 and hanger lug 29 straddling rod 14, as shown in Figs. 1 and 2. The frame will thus pivot around rod 14 to bring the arms 22 in contact with the platen with the upper portions of the ribbons 63 and 64 along the typing line.

The curvature of arm 22 permits the bail rod 12 to take its proper position, with its rollers 13 in firm contact with the journal sheet J.

As the ribbon carrying frame is hung on supporting rod 14, the frame is free to move horizontally along the platen, in response to such forces as those of momentum and inertia, generated during normal carriage

movement in typing and in carriage tabulation. Preferably this movement of the frame along the platen is limited to a distance equal to approximately one type space, the movement being preferably controlled by spaced collars (not shown) mounted on rod 14 for abutment by clips 27. A somewhat lesser amount of vertical movement of the ribbon, with respect to the line of type impact may also be provided by making the interior of said clips 27 in which the rod 14 rests, slightly wider than the diameter of said rod.

With the machine in open throat position as shown in Fig. 2 and the transparent plate 15 pivoted away from the platen 11, the ribbon holders 42 by virtue of the inward inclination of their pivotal axes, will have automatically pivoted outwardly away from arms 22 by reason of the force exerted by the bowed resilient frame 20 against its tensed ribbon 63, lever 47 pressing against plate 15.

As ribbon 64 on arms 58 remains in juxtaposition to the platen 11 against the journal sheet J thereon and as ribbon 63 will be spaced from the platen 11 and from the front plate 15 as is shown in Fig. 2, it is a relatively simple matter to position a statement form S and a ledger form L which, if desired, may be previously collated, so that the ledger form L is between ribbons 63 and 64 and the statement form S is between plate 15 and ribbon 63.

As the plate 15 is moved from the position shown in Fig. 2 to that shown in Fig. 1, it will push lever 47 inward and pivot the ribbon holders 42 to operative position so that ribbon 63 will be moved to close proximity to ribbon 64. When the type head (not shown) strikes against the primary ribbon (not shown) it will imprint the statement form as usual and through ribbons 63 and 64 cause a similar ink imprint to be made on the ledger form and the journal sheet.

The successive movements of the platen after each depression of the type key will cause the ribbon frame 21 to move both with the platen and independently on the platen and hence expose fresh areas of the ribbon to the type heads.

By reason of the slightly inturned end 54 of arm 52 which covers the tab end of the ribbons, such tab ends will not catch in the machine and jamming is avoided.

The embodiment shown in Figs. 10 and 11 is especially for use with a machine in which free access to the platen is prevented by obstructing rods, as in the Burroughs Bookkeeping Machine which has a platen 71, a pair of rods 72 and 73 and a third rod 74 all extending longitudinally thereof. It is difficult to insert a ribbon frame with rigid arms so curved as to fit the platen, past such obstructing rods and for the curved arms and the ribbon to pass between rods 73 and 74 and the platen and lie flush with the underside of the platen as is shown in solid lines in Fig. 10.

To facilitate installation of the ribbon frame, frame 76 comprises a spring metal angle bar 77 of length nearly equal to that of the platen 71 and parallel arms 78 of spring steel extending at right angles thereto. That portion 81 of each arm which is below angle bar 77 is curved to conform to the platen 71. Each portion 81, preferably at its inner edge, has an upstanding stop 82. The arms 78 desirably are affixed to angle bar 77 as by rivets and conform in shape at such affixed end to said bar 77. Preferably integral with arm 78 and extending rearwardly therefrom as shown in Fig. 10 is attachment arm 85, the free end of which is reversely bent as at 86. Arm 85 has a longitudinal slit 87 which extends through the reversely bent portion 86 thus forming a wider hanger 88 at one side of the slit and a narrower spring clip 89 at the opposite side, the end 91 of the clip being curved slightly as shown. Although arms 78 and angle bar 76 are shown as separate members, it is of course to be understood that they could be formed from but a single piece.

At both edges of the end of curved portion 81 of each arm 78 are upstanding aligned ears 92 and 93. A ribbon holder 94 has integral pivots 95 at its mounted end, extending respectively through openings in ears 92 and 93 securely yet pivotally to retain the ribbon holder 94 on arm 78.

The free end 96 of ribbon holder 94 is substantially the same as the end 49 of arm 46 shown in Fig. 9 which has been previously described in detail.

10 Ribbon 98 is installed upon the ends 96 of ribbon holder 94 in the manner previously described. To mount the frame above described, on the machine, the ribbon 98 must be passed between bar 74 and the platen 71. This would be difficult if not impossible to accomplish, were

15 the ribbon holders 94 integral with the arms 78 or permanently affixed in the position shown in full lines in Fig. 11, by reason of the limited space available for manipulation, and the obstructing presence of the pair of rigid bars 73 and 74.

20 By reason of its pivotal connection to arm 78, the ribbon holder 94 can be moved to the position shown in dot and dash lines in Fig. 11 in which it lies in substantially the same plane as arm 78. The ribbon 98 may then readily be passed between rod 74 and platen 71 to apply the spring clip portion 89 and hanger 88 of attachment arm 85 around bar 73, with stop 82 against bar 74. Thereafter the ribbon holders 94 may be pivoted to full line position so that ribbon 98 therebetween is moved against the platen.

25 30 The frame 76 will thus be securely retained in position on the machine against pivotal movement about bar 73 but movable longitudinally with the platen, which is free to rotate, and movable to limited extent independently thereon as previously described.

35 35 By the use of the devices hereinabove described, duplicate inked copies may be made on a bookkeeping machine without the need for carbon paper that is relatively costly and short-lived, slow and difficult to handle and smudges the hands of the user and the forms being typed and loses its legibility by further smudging with each handling of the finished form.

40 45 The ribbons herein utilized, enable erasures to be made by simply turning the platen to expose the erroneous entry beyond the ribbon. As there is no duplicating medium such as carbon paper beneath the erroneously typed character, it can be erased without the precautions needed when carbon paper is used. Thus, the speed of correcting is considerably enhanced.

45 50 The term "bookkeeping machine" as used herein is not limited to machines that record as such, numerical accounting entries, but embraces within its scope, other machines in which the attachment herein disclosed has utility, among which are punch card controlled tabulators, typewriters or computers.

55 55 Although the device shown in Figs. 1 to 9 utilizes two ribbons, it is of course to be understood that a single ribbon or a greater number of ribbons could be utilized. In operations where two front fed forms only are used, with no need of a journal sheet ribbon, the arms 58 may be omitted. In operations where only a journal sheet ribbon is required, a much simpler form of attachment, as shown in said Patent No. 2,626,035, issued January 20, 1953 may be used. Similarly, the device shown in Figs. 10 and 11 could utilize a plurality of ribbons mounted upon the same arms.

60 65 As shown in dot and dash lines at 60 on Fig. 4, the ribbon may be cut away at one or more regions along its typing edge to disclose to view certain parts of the line being typed, as for instance, at certain columns on the journal sheet. Such cut-away area does not detract from the efficacy with which the ribbon is mounted and retained under-tension. Nor will the ribbon ravel if such areas are cut away by the ultimate user to suit his purpose, 70 75 since the impervious backing on the ribbon that serves to

prevent offset effectively retains the component strands of the ribbon in position.

As many changes could be made in the above construction, and many apparently widely different embodiments of this invention could be made without departing from the scope of the claims, it is intended that all matter contained in the above description or shown in the accompanying drawings shall be interpreted as illustrative and not in a limiting sense.

Having thus described my invention, what I claim as new and desire to secure by Letters Patent of the United States is:

1. A ribbon carrier for a front feed bookkeeping machine of the type including type keys, a carriage having a platen and a rigid rod above and spaced from said platen and extending longitudinally thereof; said ribbon carrier comprising a unitary resilient U-shaped frame including a horizontal bar and end arms extending substantially at right angles thereto, ribbon holding means pivotally connected to the ends of said arms, and unitary means on said frame resiliently to grip said rod releasably to suspend the frame with its arms in front of said platen, said arms being of length such that the pivot of the ribbon holding means is below the line of writing of the machine, whereby the ribbon may pivot to a position substantially in the sheet insertion plane of the machine.

2. The combination set forth in claim 1 in which said arms and said ribbon holding means are of lengths such that the upper half of a ribbon spanned therebetween will be struck by the type keys, whereby the last line of writing will become visible when the platen advances by a single space.

3. An auxiliary ribbon carrier for a bookkeeping machine of the open throat type including a platen having a bail rod, a carriage rod, an insertion guide plate pivotally mounted on said machine in front of said platen extending longitudinally thereof, and movable from open to closed position, said carrier comprising a frame including a longitudinal bar and end arms extending therefrom, means on said frame coacting with said carriage rod to suspend the frame in front of such platen, ribbon holding means on each of said arms for releasable attachment thereto of the ends of a ribbon, and a second ribbon holding means near the end of each of said arms for releasable attachment thereto of the ends of a second ribbon, said second holding means having a mount below the writing line of the machine to permit movement toward and away from said first holding means, between said platen and said insertion guide plate.

4. The combination set forth in claim 3 in which the means on said frame to suspend it in front of said platen comprises a resilient clip at the upper end of each end arm, engaging and clasping said carriage rod.

5. The combination set forth in claim 3 in which each of said first ribbon holding means comprises a resilient arm affixed to, having a portion spaced laterally from and extending substantially parallel to and weaker than the outer edge of the associated end arm, whereby said first ribbon will be maintained taut, without substantially affecting the tension of said second ribbon.

6. The combination set forth in claim 3 in which each of said first ribbon holding means comprises a substantially L-shaped member of resilient spring metal having one leg extending transversely across the associated end arm and affixed thereto and its other leg spaced laterally from and extending substantially parallel to the outer edge of the associated end arm, said spaced leg having means near the free edge thereof for mounting the respective ends of a ribbon to be spanned therebetween.

7. The combination set forth in claim 6 in which said ribbon holding leg is of lesser stiffness than that of the associated arm.

8. The combination set forth in claim 3 in which lever means are associated with said second ribbon support-

ing means and adapted to be engaged by such insertion guide plate when the latter is moved to closed position to move said second ribbon supporting means and the ribbon thereon to operative position.

5 9. The combination set forth in claim 3 in which said second ribbon holding means is pivotally connected at one end to the end of said end arm.

10. The combination set forth in claim 9 in which stop means are associated with each of said end arms to limit the outward movement of the associated pivotally connected ribbon holding means, whereby the outward movement of said second ribbon is limited to a position in which it is spaced from the insertion guide plate with its width substantially parallel to the insertion guide plate.

15 11. The combination set forth in claim 9 in which the pivotal axis of each said second ribbon holding means is inclined inwardly, whereby the tension of a ribbon spanned therebetween will normally urge it away from said end arms.

20 12. As an article of manufacture, an auxiliary ribbon holder for a bookkeeping machine, said holder comprising a frame including a longitudinal bar and end arms extending angularly therefrom, means for releasable attachment of said frame to such machine, ribbon holding means on each of said arms for releasable attachment of the ends of a ribbon to be spanned therebetween, and a reversely bent member pivotally connected at its reversely bent end to the end of each of said end arms, said member having an inner ply and an outer ply, said inner ply defining a second ribbon holding means for releasable attachment thereto of the ends of a ribbon to extend between said second ribbon holding means, said reversely bent member extending over said first ribbon holding means and movable toward and away therefrom.

25 13. The combination set forth in claim 12 in which the outer ply is of greater length than the inner ply and extends beyond the latter to define a lever.

30 14. The combination set forth in claim 12 in which each of said end arms has a pair of transversely aligned ears near its free end and the reversely bent end of said member is pivotally mounted by said ears.

35 15. The combination set forth in claim 12 in which a reversely bent strip extends from the free end of each end arm and defines a stop for the associated pivotally mounted reversely bent member to limit its outward movement.

40 16. The combination set forth in claim 12 in which each of said first ribbon holding means comprises a substantially L-shaped member of resilient spring metal having one leg affixed thereto and its other leg spaced laterally from the associated end arm and extending substantially parallel to the outer edge thereof, the ribbon being attached to the free end of said other leg, and said reversely bent member has an arm extending laterally outward from the outer ply thereof substantially aligned with the ribbon holding end of said other leg.

45 17. The combination set forth in claim 16 in which the outer edge of said lateral arm extends inwardly.

50 18. An auxiliary ribbon carrier comprising a frame including a longitudinal bar and end arms unitary therewith and extending angularly downward therefrom, hinge elements substantially on the free ends of said end arms, and ribbon carrying members hingedly connected to said hinge elements and extending upward from the ends of said arms.

55 19. An auxiliary ribbon carrier comprising a frame including a longitudinal bar with end arms unitary therewith and extending angularly downward therefrom, a ribbon carrying member substantially rigid with each of said arms intermediate the length thereof, said ribbon carrier members being adapted to mount the ends 60 of a first ribbon spanning the interval therebetween,

75 of a first ribbon spanning the interval therebetween,

hinge elements substantially on the free ends of said end arms and ribbon carrying members hingedly connected to said hinge elements and adapted to mount a second ribbon spanning the interval therebetween to extend substantially parallel to such first ribbon.

20. An auxiliary assembly of ribbon and carrier therefor, for use with a bookkeeping machine of the type having a platen and a bar above said platen, said carrier comprising a frame including a longitudinal bar and end arms extending angularly therefrom, each having an outer free end, hinge elements on said free ends, ribbon carrying members hingedly connected to said hinge elements and extending upward from the ends of said arms, a ribbon connected to the hinged ribbon carrying members, and means for releasably engaging said carrier with said bar, said carrier when engaged with said bar maintaining the ribbon along the writing line of the machine.

21. The combination set forth in claim 20, in which the ribbon has a notch along the upper edge to expose to view the typing line.
